UNITED STATES PATENT OFFICE.

JOSEPH L. WRIGHT, OF CLEVELAND, OHIO, ASSIGNOR, BY MESNE ASSIGNMENTS, TO
WESTERN ELECTRIC COMPANY, INCORPORATED, A CORPORATION OF NEW YORK.

TELEPHONE-EXCHANGE SYSTEM.

1,191,265.

Specification of Letters Patent. Patented July 18, 1916.

Application filed June 9, 1914. Serial No. 844,006.

To all whom it may concern:

Be it known that I, JOSEPH L. WRIGHT, a citizen of the United States, residing at Cleveland, in the county of Cuyahoga and 5 State of Ohio, have invented certain new and useful Improvements in Telephone-Exchange Systems, of which the following is a specification.

My invention relates to telephone exchange systems and especially to that type 10 wherein automatic switching mechanism is used for effecting connections between calling and called subscribers or between various trunks.

Heretofore it has been customary to transmit impulses from a sending device in a predetermined order to operate the automatic switches. These sending devices may either be at the central office or at a subscriber's station and transmit impulses by grounding 15 one or both sides of the line, or as in metallic systems by opening and closing the line or trunk circuit. With the latter method special apparatus having various time elements 20 has to be provided at the central office. This apparatus usually consists of quick and sluggish acting relays which have to be timed very carefully in order that the automatic switching mechanism which they control is properly operated. 25

With my invention I preferably use a metallic circuit but do not open and close the line circuit as the control circuit is normally closed while the switches are being operated.

To accomplish this end I provide a sound or 30 audible signal producing device at the substation or at the central office as the case may be. Associated with the automatic switching mechanism is apparatus which responds to the sound producing device. The apparatus which responds to the sound producing device corresponds to the ordinary receiver and is provided with a set of contacts which open and close in response to the action of 35 the sound producing device. With this method of controlling the automatic switching mechanism the subscriber upon removing his receiver operates the device and the circuit of this line is not opened until he finally 40 hangs up his receiver, thereby providing a

positive method of release for the automatic switches.

My invention is illustrated in the accompanying drawings wherein:

Figure 1 shows a subscriber's station terminating in a first selector switch. Fig. 2 shows a connector circuit which operates in conjunction with the first selector circuit. Fig. 3 shows a sound producing device suitable for use with my invention. Fig. 4 shows a modification of the apparatus which responds to the sound producing device. 55 60

Referring to Fig. 1, the subscriber's station at A is equipped with apparatus usual in common battery systems comprising the usual receiver, transmitter, switch hook and ringer, and in addition is equipped with the sound producing device shown in detail in Fig. 3, and represented in Fig. 1 by the letter P. 65

The subscriber's line terminates at the central office in the first selector switch K. This switch corresponds to that of the well-known Strowger type but instead of first stepping vertically and then rotating, it 70 first rotates and then steps in a vertical direction. Relay 1—B, is the tip relay responsive to the closing of the calling subscriber's line. The receiving device is shown at D in a diagrammatic manner. The magnet 15 is 75 surrounded by disk type permanent magnets used in watch case receivers. The diaphragm 17 is provided with a contact point 19 which engages contact 18 when in its operative position. The receiving device is in 80 reality a polarized relay constructed on the principle of a telephone receiver. The diaphragm corresponds to and performs the same function as the armature of a relay. The diaphragm in vibrating operates its 85 associated contacts which in turn control other mechanism. The magnet 15 consists of a core with a suitable winding in the ordinary manner. The disks 16 which surround the magnet are ring shaped permanent magnets 90 which serve to magnetize or polarize the magnet 15. The diaphragm 17 may be clamped and held in place in a manner similar to a diaphragm in ordinary telephone 95 receivers. 100

Any form of adjustment may be used to regulate the space between the contact points 18 and 19 in order to cause these contacts to properly operate in response to the signals transmitted.

Relay F is a repeating relay, while relay G is a slow relay for controlling the various circuits. Relay E is the test relay while relay 200 is the cut-off relay serving to disconnect the first selector switch equipment on incoming calls.

Referring to Fig. 2, the receiving device is shown at L and is a duplicate of that shown in Fig. 1. O is the tip relay and responds to the closure of the called line. M is the repeating relay while relay N is used for shifting various control circuits. Relay T is the ringing relay while U is used for completing the trunk conductors when connection is effected with the called line. V is the transfer relay while relay 300 is the test relay.

Fig. 4 shows the manner in which the motion of the diaphragm in the receiving device is multiplied. An arm is provided and pivoted at 100. The shorter portion of the arm terminates in a button 102 which normally rests in engagement with the diaphragm 17. At each operation of the diaphragm the arm follows and the portion at 101 which is considerably longer than that at 103, moves a greater distance and at each movement closes the contact springs 18 and 19.

The operation of my system is as follows: The subscriber at A removing his receiver closes his line circuit thereby energizing relay 1-B. The energizing of this relay connects ground to contacts 48 which are multiplied in the banks of the connector switches so as to render the line busy against other calls. The operation of relay 1-B also disconnects or breaks the circuit of the release magnet J. Battery is supplied to the calling subscriber for talking purposes through the windings of relay 1-B and the retardation coil C. The talking conductors are separated by condensers 7 and 8 in the usual manner. The calling subscriber after removing his receiver operates the sound producing device P a number of times corresponding to the number desired in the usual manner.

The winding of the magnet 15 of the receiving device is connected to the talking conductors 9 and 10, one terminal being permanently connected to the conductor 10 while the other terminal is connected to the conductor 9 through the cam springs 35 and 36. At each operation of the sound producing device at the subscriber's station a corresponding action is set up in the receiving device at D. The receiving device D in acting completes the circuit of relay F and slow relay G as follows: ground, 18,

19, 20, winding of relay F, 21, winding of relay G, to battery B. The operation of relay F completes the circuit of the rotary magnet H as follows: ground, contacts of relay F, 22, contacts of relay E, 25, winding of magnet H to battery B. The operation of magnet H causes the switch K to rotate and bring the wipers 13 and 14 in line with a row of contacts corresponding to the action of the sound producing device. At each stroke of the magnet H its associated contact springs are closed thereby connecting ground between the windings of relays F and G. This ground connection shunts out relay F but maintains relay G energized. Relay G is first energized in series with relay F by the action of the receiving device and then held energized by the action of the springs associated with the rotary magnet H. The magnet G, being slow, remains energized throughout the interruptions caused by the opening of contacts 18 and 19 of the receiving device D. The relay F is provided with a locking contact and when energized by the closing of contacts 18 and 19 its circuit is maintained to ground independent of the contacts 18 and 19. This locking contact is provided in view of the fact that contacts 18 and 19 may be only momentarily closed, that is to say, not closed long enough to allow the full operation of the magnet H. This momentary closure, however, is sufficient to energize relay F and as soon as the magnet H has finished its stroke ground is connected and relay F shunted out or released.

After the first operation of the sound producing device at the subscriber's station A there is a momentary pause due to the subscriber setting up the number for another series. During this pause relay G falls back. Relay G in falling back completes the circuit of relay E as follows: ground, cam springs 40, 39, and 38, conductor 37, back contacts of relay F, 32, contacts of relay G, 31, vertical cam springs 30 and 29, 28, winding of relay E to battery B.

The rotary cam springs 38, 39 and 40 are closed at the first rotary step of the switch K. The vertical cam springs 30, 29, 28 and 35 are opened at the first vertical step of the switch K.

The operation of relay E severs the trunk conductors, disconnects the rotary magnet H and in its place connects the vertical magnet I. The operation of relay E also completes the circuit of relay F as follows: ground, contacts of relay E, 33, 20, winding of relay F, 21, winding of relay G to battery B. The operation of relay F now completes the circuit of the vertical magnet I as follows: ground, contacts of relay F, 22, contacts of relay E, 23, winding of magnet I to battery B. The operation of magnet I causes the switch K to step vertically and

also by means of its associated contact springs, connects ground between the windings of relays F and G. This ground connection shunts relay F thereby opening the 5 circuit of magnet I, but as soon as magnet I restores, ground is removed from the winding of relay F and it at once becomes energized, again completing the circuit of magnet I. This action set up between relay F 10 and magnet I causes the latter to vibrate and step the switch K vertically until relay E becomes deenergized. The circuit of this relay is maintained closed to ground through the back contacts of relays F while the 15 wipers 14 are passing over busy or grounded contacts. As soon as an idle ungrounded contact is found, relay E will restore and remove ground from the winding of relay F. Relay F, in falling back, applies ground to 20 test brush 14, thus causing the seized trunk to test busy. The next operation of the sound producing device at the subscriber's station causes the operation of the receiving device L in Fig. 2. The action of the 25 receiving device L completes the circuit of relay M and slow relay N as follows: ground, 61, 60, 64, winding of relay M, 65, winding of relay N to battery B. The operation of relay M completes the circuit of 30 the rotary magnet W as follows: ground, contacts of relay M, 66, contacts of relay V, 67, winding of magnet W to battery B. The operation of magnet W closes its associated contact springs thereby connecting ground 35 between the windings of relays M and N. This ground shunts out the windings of relay M but maintains the relay N energized. After the final operation of the receiving device L, relay N falls back and completes 40 the circuit of the relay V as follows: battery B, contacts of relay N, 68, cam springs 69, and 70, conductor 71, cam springs 72 and 73, winding of relay V, 57, test contacts, wiper 14, 27, to ground through the back contacts 45 of relay F (Fig. 1). Relay V then locks up. The operation of relay V disconnects the winding of the rotary magnet W and in its place connects the vertical magnet X. The next operation of the receiving device L in 50 response to the action of the sound producing device at the subscriber's station completes the circuit of relays M and N as before. The operation of relay M now completes the circuit of the vertical magnet X as follows: ground, contacts of relay M, 66, contacts of relay V, 75, winding of magnet X to battery B. The operation of magnet X besides stepping the 55 switch Z in a vertical direction also closes its associated contact springs thereby connecting ground between the windings of relays M and N. After the third operation of the sound producing device at the subscriber's station relay N falling back completes 60 the circuit of relay S as follows: ground, 76,

winding of relay S, 77, wiper 78, contact 47, 44, winding of relay 200 to battery B. The operation of relay S completes the circuit of the ringing relay T as follows: ground, 70 commutator 90, winding of relay T, 89, contacts of relay S, 88, contacts of relay R to battery B. The operation of relay S also completes the circuit of relay U in case the called for line is not busy as follows: 75 ground, contacts of relay 300, 86, contacts of relay S, 87, winding of relay U to battery B. The operation of relay U completes the trunk conductors and also connects ground to the test wiper 80 of the switch Z thereby rendering the called for line busy against 80 other calls.

In case the called for line is busy ground would be connected to the test contacts engaged by the wiper 80 and in such an event after relay N had fallen back the circuit of 85 the test relay 300 would be completed as follows: ground from the test contact engaged by the wiper 80, 81, back contacts of relay U, 82, contacts of relay N, 83, winding of relay 300 to battery B. Relay 300 becoming energized would complete the circuit of release magnet Y thereby restoring the connector switch Z to its normal position. The operation of relay 300 connects a suitable 90 busy tone signal to the trunk conductors 95 notifying the calling subscriber that the called for line is busy.

The action of relay 300 besides performing the foregoing functions, also prevents the operation of relay U by removing ground 100 from the conductor 86.

It will be noticed that when relay N finally restores after the wipers of the switch Z engage the contacts of the called line that the action of relay S and relay 300 would be 105 completed at the same time, but that the action of relay U is not completed until after the action of relay S. This arrangement causes sufficient time interval for the operation of relay 300 in case the called for 110 line is busy and before relay U can operate.

Upon the first operation of relay N the circuit of relay R is completed as follows: battery B, contacts of relay N, 58, winding of relay R to ground over test wire 57. The 115 operation of relay R partially completes the circuit of relay T and partially opens the circuit of release magnet Y. One terminal of magnet Y is connected to ground through the rotary cam springs 94 controlled by 120 the switch Z. These cam springs are closed at the first rotary step of the switch Z.

We will assume that the called for line is not busy and that relays S and U are 125 energized. In such an event the circuit of the ringing relay T is completed periodically by the action of the commutator 90. At each operation of relay T ringing current supplied by generator 400 is connected 130 to the called line. When the called sub-

scriber removes his receiver relay O is energized, the operation of which closes the tip trunk conductor and also removes battery from the locking contact of relay R. Relay R restoring opens the circuit of relay T thus preventing further application of ringing current. Battery is supplied to the called subscriber through the winding of relay O and winding of the retardation 10 coil Q. At the termination of the conversation the calling subscriber hanging up his receiver opens the circuit of his line thereby causing the deenergization of relay 1-B. This relay in restoring completes the circuit 15 of the release magnet J as follows: ground, 40, 39, 41, contacts of relay 1-B, 42, winding of magnet J to battery B. The action of this release magnet restores the first selector switch K thereby restoring all its parts to 20 normal.

The called subscriber hanging up his receiver causes the deenergization of relay O and this relay in restoring completes the circuit of the release magnet Y as follows: 25 battery B, contacts of relay O, 85, contacts of relay R, 84, winding of magnet Y, rotary cam springs 94 to ground. The operation of magnet Y restores the switch Z to its normal position thereby causing relays S 30 and U to return to their normal condition.

In case the called for subscriber does not answer then the calling subscriber in addition to releasing the first selector switch K also releases the connector switch Z. When 35 the calling subscriber hangs up his receiver restoring the first selector switch K ground is removed from test wire 57 of the connector switch thereby releasing relay R. This relay in restoring completes the circuit 40 of the release magnet Y just as though the called for subscriber had answered and then hung up his receiver.

Having thus described my invention, what I desire to secure by Letters Patent is:

45 1. In a telephone exchange system, the combination with an automatic switch, a stepping magnet therefor, and a sound producing device, of a plurality of trunk circuits selectable by said switch, a receiving 50 device associated with said switch and responsive to said sound producing device adapted to transmit impulses to said stepping magnet to cause said automatic switch to select any one of said trunk circuits, substantially as set forth.

55 2. In a telephone exchange system, the combination with an automatic switch, a stepping magnet therefor, and a receiving device, of a sound producing device adapted 60 to actuate the same, a plurality of circuits selectable by said switch, said receiving device being adapted to transmit impulses to said magnet to cause said automatic switch to select any one of said circuits, substantially as set forth.

3. In a telephone exchange system, the combination with a plurality of subscribers' lines, of automatic switching mechanism for selecting said lines, sound producing means, a stepping magnet for operating said switching mechanism, additional means associated with said automatic switching mechanism responsive to said sound producing means for operating said stepping magnet to cause said automatic switching mechanism to select said lines, substantially as set forth. 70

4. In a telephone exchange system, the combination with a calling and a called subscriber's line, of automatic switching mechanism for selecting the called line, a stepping magnet therefor, means associated with said automatic switching mechanism and responsive to audible signals over the calling line for transmitting impulses to 80 said magnet to cause said automatic switching mechanism to select the called line, substantially as set forth. 85

5. In a telephone exchange system, the combination with an automatic switch, a stepping magnet therefor, of a plurality of circuits selectable by said switch, an audible controlling device, means associated with said switch and responsive to said audible device for transmitting impulses to said magnet to cause said automatic switch to 90 select any one of said circuits, substantially as set forth. 95

6. In a telephone exchange system, the combination with an automatic switch movable in two directions, of a sound producing device, means associated with said switch and responsive to said sound producing device for controlling the action of said switch in both directions, substantially as 100 set forth. 105

7. In a telephone exchange system, the combination with an automatic switch movable in two directions, means for actuating said switch in both directions, sound producing means, said actuating means being responsive to said sound producing means, substantially as set forth. 110

8. In a telephone exchange system, the combination with a two-motion step-by-step automatic switch, means for actuating said switch, a device for producing audible signals, additional means associated with said switch for controlling said actuating means in response to said audible signals, substantially as set forth. 115 120

9. In a telephone exchange system, the combination with a two-motion step-by-step automatic switch, a device for producing audible signals, said actuating means being tuned to and responsive to said audible signals, substantially as set forth. 125

10. In a telephone exchange system, the combination with a two-motion automatic switch, of a device for producing a pre- 130

5 determined number of audible signals, actuating means for said switch, additional means associated with said switch responsive to said audible signals for actuating said switch, according to the number of audible signals, substantially as set forth.

10 11. In a telephone exchange system, the combination with a two-motion automatic switch, of a device for producing distinctive audible signals in a predetermined order, means associated with said switch tuned to and responsive to said signals for controlling said automatic switch according to the order of said signals, substantially as set forth.

15 12. In a telephone exchange system, the combination with a device for producing a predetermined number of audible signals, of an automatic switch provided with a plurality of contacts selectable by said switch, means for actuating said switch, additional means associated with said switch responsive to said audible signals for rendering active the actuating means to cause said switch to select a contact corresponding to the number of audible signals, substantially as set forth.

20 13. In a telephone exchange system, the combination with a plurality of subscribers' lines, of an automatic switch for selecting said lines, a control circuit extending to said switch, means associated with said control circuit for causing current variations therein, a receiving device, means for inductively associating said receiving device with said means whereby the same is responsive to said variations in the control circuit for causing said switch to select any one of said lines, said variations occurring 25 while said control circuit is closed, substantially as set forth.

25 14. In a telephone exchange system, the combination with an automatic switch, actuating and releasing means for said switch, a control circuit comprising two conductors extending to said switch, means for closing said conductors, a device for causing current variations in said control circuit during the closure of said conductors, a relay 30 responsive to the closing of said conductors for controlling the releasing means, a receiver, means for inductively associating said receiver with said device whereby the same is responsive to the variations for controlling the actuating means for said switch, substantially as set forth.

35 15. In a telephone exchange system, the combination with an automatic switch, actuating and releasing means for said switch, of a control circuit comprising two conductors extending to said switch, a subscriber's station associated with said control circuit, said station comprising a circuit closing device for closing said conductors and a sound producing device, means asso-

ciated with switch responsive to the circuit closing device for controlling the releasing means, and additional means comprising a receiving device responsive to the sound producing device for controlling the actuating means during the closure of said conductors, substantially as set forth.

40 16. In a telephone exchange system, the combination with an automatic switch, actuating and releasing means for said switch, a control circuit comprising two conductors extending to said switch, means in said control circuit for closing said conductors, additional sound producing means for causing variations in said control circuit during the closure of said conductors, a relay associated with said switch responsive to the closure of said conductors for controlling the releasing means, a receiving device associated with said switch responsive to variations in said control circuit for controlling said actuating means, substantially as set forth.

45 17. In a telephone exchange system, the combination with calling and called subscribers' lines, of automatic switching mechanism comprising selector and connector switches for interconnecting said lines, audible signal devices associated with said lines for causing variations therein, means associated with said switches for controlling their action to interconnect said lines, said means comprising receiving devices responsive to said variations, substantially as set forth.

50 18. In a telephone exchange system, the combination with calling and called subscribers' lines, of automatic switching mechanism for interconnecting said lines, audible signal devices associated with said lines, receiving devices associated with said automatic switching mechanism responsive to said signal devices for automatically causing any one of the calling lines to become connected to any one of the called lines, substantially as set forth.

55 19. In a telephone exchange system, the combination with an automatic switch and a control trunk leading thereto, actuating means for said switch, sound producing means associated with said control trunk for causing variations therein, a receiving device associated with said switch responsive to said variations for controlling the actuating means for said switch, substantially as set forth.

60 20. In a telephone exchange system, the combination with a calling and a called subscriber's line, sound producing means therein, of automatic switching mechanism for interconnecting said lines, said automatic switching mechanism comprising selector and connector switches, means associated with said switches controlled by said sound producing means for causing said switches to interconnect said lines, substantially as set forth.

21. In a telephone exchange system, the combination with a calling and a called subscriber's line, of automatic switching mechanism comprising selector and connector switches for interconnecting said lines, an audible signal device associated with the calling line, of means associated with said switches responsive to said device for causing the selection of the called line by said switching mechanism, substantially as set forth.

22. In a telephone exchange system, the combination with calling and called subscribers' lines, of automatic switching mechanism comprising selector and connector switches for interconnecting said lines, an audible signal device, means associated with said switching mechanism responsive to said device for causing the interconnection of said lines, substantially as set forth.

23. In a telephone exchange system, the combination with an automatic switch, actuating means for said switch, of a sound producing device, a receiving device associated with said switch and controlled by said device for rendering operable said actuating

means, a locking relay associated with said switch, means controlled by said receiving device for energizing said relay, and additional means controlled by the actuating means for deenergizing said relay, substantially as set forth. 30

24. In a telephone exchange system, the combination with a calling and a called subscriber's line, of automatic switching mechanism forming the link for interconnecting said lines, a stepping magnet for said switching mechanism, sound producing means associated with the calling line, means associated with said automatic switching mechanism responsive to said sound producing means for transmitting impulses to said magnet to cause said automatic switching mechanism to form the link for interconnecting said lines, substantially as set forth. 35 40 45

In testimony whereof I affix my signature in presence of two witnesses.

JOSEPH L. WRIGHT.
